MECHANICAL TOY

Filed Dec. 9, 1925

Fig. 1.

Fig. 4.

UNITED STATES PATENT OFFICE.

SAMUEL I. BERGER, OF NEWARK, NEW JERSEY.

MECHANICAL TOY.

Application filed December 9, 1925. Serial No. 74,236.

My present invention relates to improvements in motor driven mechanical toys particularly to toys of the character in which the motor becomes intermittently operative 5 to move a toy figure to assume power position from which the power stored by the figure is delivered during the intervals between effective operations of the motor.

Objects of the invention are to provide 10 a toy of the character mentioned of simple and practical construction which will be rugged and durable in use, capable of being manufactured with comparative economy and which will prove realistic in performance, and interesting and amusing to watch.

More particularly, the toy of the present invention is one in which a toy figure stores up the power intermittently received from a spring motor and intermittently delivers 20 it to operate mechanism totally unconnected with the motor. In a preferred embodiment, the figure under the impetus of the motor lifts a toy sledge or mallet and during the intervals that the motor becomes disconnected from the figure the mallet drops by 25 gravity, and actuates other mechanical devices. Preferably the movement of the figure in lifting the hammer is accompanied by other realistic movements. For instance, where the hammer is used to operate a toy 30 strength testing machine which includes a graduated upright and a bell at the top, the head of the figure will tilt forward to appear to observe the object to be struck before the hammer falls and will be subsequently 35 inclined rearward to appear to observe the scale and bell at the top of the upright after the blow has been delivered.

The invention may be more fully understood 40 from the description in connection with the accompanying drawings wherein,

Fig. 1 is a view in longitudinal section of the toy,

Fig. 2 is a transverse sectional view on 45 line 2—2 of Fig. 1,

Fig. 3 is a perspective view on a larger scale of a fragment of the guide way, and;

Fig. 4 is a perspective view of the head 50 tilting mechanism.

The reference character 10 designates a box like platform or base which constitutes a motor casing, and may be of any suitable shape, although preferably rectangular. Secured at one end thereof is the lower end 55 of an upright 11 graduated as indicated at

12, and having a central slot or guideway 11' therein in which a travelling indicator 14 is movable, to sound a bell 13 when it reaches the top of the upright. The base or motor casing is provided with a cover 60 15 having ears 16 struck upward therefrom which serve to mount the intermediate portion of a lever 17. The extremity of the longer end of the lever is disposed in slot 11' beneath the movable indicator 14 and the 65 shorter end of the lever includes a widened striking portion adapted to be hit by a sledge 8 in the hands of a toy figure 18 fixedly secured to the platform 15. In this manner, I carry out in miniature the usual construction 70 of a strength testing machine, the lever when struck by the sledge operating to propel the traveling indicator 14 upward in order to ring the bell.

The toy figure includes integral body and 75 leg portions formed of a pair of complementary stampings 19 having their edges interlocked by bendable tongues 20 or similar devices, as shown in detail and claimed in my copending application Serial No. 41,474 80 filed July 6th, 1925. The feet of the figure are provided with integral tongue extensions 21 engaging with the platform to secure the figure in place thereon, as in said copending application. A transverse shaft 22 formed 85 of a stamping has forked ends which extend laterally for pivotal mount in holes 22' in the body. The shaft has bifurcated ends 23' by which a pair of arms 23 are pivoted to shaft 22 for rocking rigidly therewith. 90

Integral extensions 24 of arms 23 constitute the handle of the sledge, the extensions being interlocked by bendable tongues 25, the head of the sledge being hollow to enclose a weight 26. The figure thus appears 95 to be holding the sledge in its hands, and to be wielding the same as the transverse shaft 22 is rocked to effect swinging movement of the arms. The head 27 of the figure is also formed of complementary stampings held 100 together by tongues 28 and is pivoted on a second transverse shaft 29 passed through the shoulder portions of the body sections, and the head is caused to move in synchronism in a manner which will be more fully 105 hereinafter described.

The spring motor which I utilize for operating the toy is of substantially conventional construction. Preferably the motor includes a drum shaft 30 and speed-retarding counter- 110

shafts 31 and 32 journaled at their ends in the side walls of the base or motor housing 10. Rotatable on the drum shaft is an elongated cylindrical drum 33 carrying at one end a driving gear 34. A coiled torsional spring 35 encircling the drum has one end affixed to a ratchet wheel 36 keyed to the shaft and its other end connected to the driving gear 34 of the drum. The usual oscillating pawl 37 prevents retrograde movement of the ratchet wheel. A key 38 disposed exteriorly of the motor casing is formed by bending the protruding end of the drum shaft into a suitably shaped loop 39 for winding the spring. To regulate and moderate the speed of the gear under the impetus of the torsional spring, I employ a train 39 of speed reducing gears, the successive gears being mounted laterally on the two countershafts 31 and 32 and connected in a speed increasing relationship so that they present a fly wheel effect. The final gear 40 of the train is preferably in the nature of an eccentric and acts as a governor. For effecting swinging movement of the arms of the figure, I mount a crank shaft 41 in brackets 42 struck inward from an end wall of the casing. This crank shaft includes a crank finger 43 presented in the path of a plurality of lifting lugs 44 struck outward from the driving gear 34 so that as said gear 34 rotates the lugs successively engage the finger to rock the crank shaft. At the other end of the crank shaft, I provide a crank arm 45 which is connected to the lower end of an upright lifting rod 46 passing up through an opening in the base through the hollow figure toy and being engaged at its upper end with a crank arm 47 on the shaft 22. The lifting rod may be in the nature of a fairly stiff wire having an eye 48 at its lower end which for purposes of convenient assembly, is hooked over the crank arm, the end of which is bent down at 41' to prevent the eye coming off. As the lifting lugs successively actuate the crank shaft 41 the lifting rod is positively elevated and consequently the arms of the figure toy are caused to lift the sledge. As the finger passes off of a lifting lug 44 the sledge by reason of its substantial weight drops by gravity striking the lever and impelling the traveling indicator 14 upward to strike the bell on the upright. To effect movement of the head of the figure, the depending neck portion 50 thereof at which it is pivoted to shaft 29 is connected to the shaft 22 by a link 51 pivoted at its upper end eccentrically of said neck portion and at its lower end to a struck-in tongue 52 in the shaft 22. As the shaft 22 rocks in a direction to effect elevation of the arms, the link 51 rocks the head 27 downward about its pivot 29. The effect of this cooperative action of the arms and head is to

cause the figure to look downward at the lever when the hammer is raised and then to cause it to lift its head quickly and look up at the bell at the time that the indicator strikes it. The indicator 14 immediately drops by gravity, strikes impelling lever 17 and restores it to normal position where its longer end rests at 59 at the lower end of slot 11' and its shorter end is raised above stop lug 16.

Novel brake mechanism is employed for retaining the gear train against movement during the time that the motor is being wound. This brake consists of a substantially L shaped lever 53 one end 54 of which is disposed horizontally within the motor casing and adapted to engage the teeth of one of the gears of the train. The other vertical arm of the brake lever includes an offset 55 having pivotal movement in the side wall of the motor casing. The vertical arm terminates in a handle end 56 passing through a suitably shaped opening 57 in the platform. The walls of this opening limit the extent of pivotal movement of the brake lever and the depending side flange 58 of the platform extends over the lever and tends to retain the brake frictionally in either position of setting.

It will thus be seen that there is herein described apparatus in which the several features of this invention are embodied, and which apparatus in its action attains the various objects of the invention and is well suited to meet the requirements of practical use. As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having thus described my invention, what I claim as new and desire to secure by Letters Patent is:

1. In a toy of the class described, a motor casing constituting a base, a cover for the motor casing, constituting a platform, a toy figure fixed on the platform, said figure including a pair of arms carrying a striking implement, a shaft connecting the arms, means passing through said figure for intermittently rocking the shaft in one direction, the striking implement being operable to return the shaft after each rocking operation thereof.

2. In a toy of the class described, a motor casing constituting a base, a cover for the motor casing, constituting a platform, a toy figure fixed on the platform, said figure including a pair of arms carrying a striking implement, a shaft fixedly connecting the arms, means for intermittently rocking the

shaft in one direction, the striking implement being operable to return the shaft after each rocking operation thereof, said figure including an oscillatable head connected to the shaft whereby the head is rocked back and forth as the arms are swung.

3. In a mechanical toy, in combination, a spring motor, a platform, a toy figure secured to said platform, said toy figure having a pivoted head and a pivoted arm, an implement rigid with said arm, a rock shaft in said figure to which said arm is rigidly connected, a linkage between said motor and said rock shaft to intermittently operate the latter for raising said arm and then releasing, and linkage between said rock shaft and said pivoted head to cause the latter to move in synchronism with the movement of the arm.

29 4. In a mechanical toy, in combination, a platform, a motor at one side thereof, a figure secured to said platform and having an element mounted for reciprocatory movement, a rock shaft having an operating arm, said motor having a rotary disk provided with one or more lifting lugs in the path of said operating arm to intermittently raise and release the same, said rock shaft having another arm connected to the reciprocating 30 element to lift the same upon actuation by the motor and to allow the same to return

by gravity after release of the rock shaft by the lifting lug.

5. In a mechanical toy, in combination, a casing, a spring motor therein, said motor including a rotary disc, a figure mounted on said casing, said figure having a pivoted, weighted reciprocatory member, means for raising said member by power from said motor including one or more struck up lugs 35 in said disk and a rock shaft having an arm in the path of movement of said lugs, a second arm on said rock shaft and linkage connecting said arm to said reciprocating member whereby the reciprocating member is 40 raised by the action of a lug on the rock shaft, and after said lug passes off the rock shaft arm, the weighted member will drop by gravity.

6. In a toy, in combination, a figure, a 50 pair of arms pivoted at the shoulders of said figure said arms having integral extensions clenched together to represent the handle of a sledge, and having enlargements at the outer ends thereof clenched together to 55 form a sledge head and a metallic weight within said clenched head.

Signed at Newark, in the county of Essex and State of New Jersey this 4th day of December, A. D. 1925.

SAMUEL I. BERGER.
